UNITED STATES PATENT OFFICE

JAMES BENTON SCHAUB, OF WILMETTE, ILLINOIS

AIR CURRENT CONVEYER

Application filed September 18, 1930. Serial No. 482,740.

My invention relates to a combination of apparatus, so arranged as to constitute a conveyer system which may be used for transporting finely divided solids, granular materials, comminuted materials, or liquid substances, in a lateral direction or a vertical direction or a combination of lateral and vertical directions, and most commonly uses conduits as conducting members, and utilizes air or gaseous fluid after having been compressed greater than the pressure of the atmosphere, as a conveying medium. It relates to conveyer systems used to move grain from one location or storage bin to another or from an unloading dock to a storage bin, or the reverse.

It also relates to conveyer systems used to move pulverized fuels and the like from one location to another, as for example from the discharge of the pulverizing apparatus, or from a suitable storage to the bins supplying the fuel to the boiler fire chamber.

It more particularly relates to conveyers used for transporting and elevating dry sand from a receptacle at approximately ground level to a receptacle sufficiently elevated to allow the sand to flow by gravity into the sand domes of railway locomotives.

The primary object of my invention, generally stated, is to provide novel and simple improvements in conveying apparatus of the general character above stated, to the end that such apparatus may be made to function in an automatic manner, and entirely independent of manual control. The type of apparatus to which my invention may be especially applied is that used at railway locomotive terminals and servicing points where dry sand is supplied to railway locomotives. By the elimination of the need of constant attention by an attendant, and by the conservation of compressed air, considerable economy may be effected.

As a preface to the following description, it may be stated that a complete conveying system of the type to which my improvements relate, may be considered as having two divisions. The one; that portion of the system located at the forwarding point and

5 materials to be forwarded or conveyed, are placed, and which may be closed and subjected to internal pressure thereby causing movement of the materials in the chamber. This portion also comprises a means for placing the materials in the chamber, also conduit connections and valves. The other, that portion of the system located at the delivery point. This portion may comprise merely the end of the conveyer conductor conduit arranged to allow the materials to be discharged into the open or it may consist of a receiving or storage chamber made of any suitable size and shape, 65 said chamber usually being elevated and provided with a suitable outlet whereby the materials may be discharged by gravity.

The invention involves the provision of an improved control device consisting of the insertion of a pressure control valve in 70 the compressed air or gas conduit line leading from the source of compressed gas or air to the forwarding chamber of the conveyer system, as set forth in my previous application for Letters Patent filed October 17, 1928, Serial No. 313,102. The invention utilizes two characteristics of the conveyer system, namely the gravitational weight of the materials to be conveyed, and the compressed air or gas which serves as the medium of transfer, as factors of the control features.

By referring to the accompanying drawings, whereon like reference characters designate corresponding parts throughout the 85 several figures,

Figure 1 is a composite elevation view illustrating a conveyer system of the character herein described and embodying an application of my improvements. It represents both divisions, the forwarding and the delivery. Figure 2 is an enlarged section view taken on line 2-2 on Fig. 1. Figure 3 is an enlarged section view taken on line 3-3 on Fig. 1. Figure 4 is an enlarged section view taken on line 4-4 on Fig. 1. Figure 5 is an elevation view illustrating another embodiment of a conveyer system of the character herein described and representing only the forwarding division. 100

- In the particular arrangement shown, a container of any suitable size and shape is designated 10. This container serves as the forwarding chamber of the conveyer system.
- 5 The liquid or granular materials to be conveyed are introduced into the forwarding chamber through an opening at or near the top of the chamber. The materials are directed to the opening by means of a suitable
- 10 housing or funnel 11. A suitable valve arrangement is provided for conveniently closing the opening when pressure is to be applied inside the forwarding chamber. This arrangement may consist of a semi-
- 15 spherical member 42 which will close against a concave seat 43 when tension is applied to the connecting member 40. A conduit 12, of suitable size and arrangement, connects forwarding chamber 10 with a chamber 13.
- 20 This chamber functions as the receiving reservoir at the delivery point of the conveyer system in such cases as the materials conveyed are to be deposited in a reservoir for storage or temporary accumulation pend-
- 25 ing later disposal. If the materials conveyed are to be dispersed into the open this receiving chamber is dispensed with and conductor conduit 12 is opened to the atmosphere or into any suitable delivery head.
- 30 The conveyer system is supplied with compressed air or gas from a suitable supply by means of conduit conductor 14. This conduit is intercepted by a valve. In Fig. 1 this valve has been illustrated as of the dia-
- 35 phragm pressure control type and designated 15. This valve is operated to an open position by pressure acting on a diaphragm member and to a closed position by means of a spring designated 19. In place of the
- 40 valve shown there can be used other types of valves capable of carrying out the functions described.

Near the bottom of forwarding chamber 10 is located a diaphragm member 20 to which is attached a rod 21 which in turn is attached to a piston type valve 24. This valve in operation has the effect of a three-way type valve. By referring to the enlarged section view Fig. 2 it will be observed that the piston 22 is provided with an opening 23 extending across it and another opening 25 which extends only part way across the piston and then curves to the end of the piston. A lever 32 provided with an intermediate pivot 34 and an adjustable weight 31 is connected in a flexible manner and by means of pin 33, at the opposite end, to the rod 21. Under normal conditions the weight will cause the piston to rest in the position illustrated with the result that conduit conductor 27 will be effectively blocked against the surface of the piston and conduit 28 will be in intercommunicating relationship with opening 25 in the piston and

by means of vent 26 be open to the atmosphere.

By referring to Fig. 1 it will be noted that conduit 28 also connects to a cylinder 46 near its bottom. By referring to section view 70 Fig. 3 it will be noted that piston 41 operating in this cylinder is connected to a rod 40 which in turn is connected to a semi-spherical member 42, previously referred to, and which is located at the opening near top of forwarding chamber 10. A lever 47 provided with an end pivot 48 and an adjustable weight 49 is connected in a flexible manner and by means of a pin 44 at an intermediate point, to the rod 40. Under normal conditions the weight will cause the valve member 42 to repose in an open position as illustrated. Piston 41 while reposed in normal position leaves a space in cylinder 46 to which conduit 28 is joined. Another conduit 16, joins cylinder 46 in such a manner as to cause unobstructed communication between it and conduit 28 after piston 41 has made a predetermined movement. Cylinder 46 is provided with an air vent 45 to prevent obstruction to the movement of piston 41. With this arrangement the valve member 42 may be made to move into at least a partly closed position before pressure is allowed to pass into the auxiliary chamber 80 of the compressed air conduit control valve 15.

A modified arrangement is shown in Fig. 5 whereby conduit 28 connects valve 24 and pressure chamber of control valve 15. With 100 this arrangement pressure may be applied into cylinder 46 to operate the piston 41, and rod 40, by means of a conduit connecting conduit 28 and the cylinder 46, or if desired the rod 40 may be operated by hand to close 105 the forwarding chamber inlet, or by any other suitable means.

Fig. 4 shows an enlarged section taken through the control element mounted in the delivery or storage chamber. A diaphragm 110 or other suitable flexible or movable member 52 is mounted inside the chamber 13 and connected to one end of rod 51 which in turn is connected to piston 53 which operates in a cylinder 50. This piston is provided with an opening 55. When the piston is in normal position this opening establishes unobstructed communication between conduits 54 and 27. The piston is held in this normal position by some such means as a spring 56. When the piston moves, which it does as a result of pressure against member 52, the communication between conduits 54 and 27 becomes obstructed. The pressure against 115 member 52 will occur as a result of conveyed materials becoming piled against or above the member. When the materials are removed the spring 56 will force the piston 53 back to normal position and unobstructed 120

125 130

communication will again be established between conduit conductors 54 and 27.

By referring to Fig. 1 it will be noted that conduit 54 establishes communication between the compressed gas supply conduit 14 and the valve member 50, and that conduit 27 establishes communication between valve member 50 and valve member 24. When delivery chamber 13 is not used as a part of the conveyer system, or when it is not necessary to control the movement of the conveyed materials contingent upon the quantity at or near the discharge end of the conduit 12, then conduit 27 is connected direct to the source of compressed gas. In Fig. 5 this connection is shown as being made to conduit 14 at some point ahead of valve 15.

In Fig. 1 the delivery chamber 13 is indicated as being supported by a tower member 17 and also as being equipped with a discharge spout 18. The details and dimensions of these members will be determined by the local requirements. Customarily a valve or cut-off of some kind will be located in the discharge spout 18 to control the flow of materials from the chamber 13.

The cycle of operation for a complete conveyer system as described and represented by Fig. 1 is as follows:—

The materials to be conveyed are deposited into hopper 11. As a matter of convenience this hopper may be located beneath a fuel pulverizer, or sand drier, or any other source or regular supply of materials to be conveyed. The materials pass through the opening and into the forwarding chamber 10. When the volume of the materials approaches the capacity of the chamber, their weight acting against counter weight of member 31 on lever 32, causes a movement of diaphragm member 20 and connecting rod 21 to the extent that piston 22 moves and allows unobstructed communication between conduit 27 and conduit 28 by way of cavity 23 in piston member 22. Compressed gas or air in conduit 27 passes through conduit 28 into chamber of cylinder member 46 causing piston 41 to move upwardly and by means of connecting rod 40 causes the semi-spherical valve member 42 to seat against valve seat 43 thereby closing the opening leading into the chamber 10. The movement of piston 41 in turn opens inlet to conduit 16 thereby permitting unobstructed communication from conduit 27 to conduit 16 through conduit 28. Compressed gas or air is thus allowed to pass into the pressure control chamber of the valve 15 thereby operating the valve 15 in the compressed gas or air supply conduit line 14 to an open position. Compressed air is thus allowed to enter forwarding chamber 10 through conduit 14. The pressure so built up in chamber 10 forces the materials to pass

out through conductor conduit 12 and be deposited in a delivery chamber 13.

When the materials have been removed or transported from the forwarding chamber the pressure therein decreases with the result that both the pressure due to the gravitational weight of the materials and the pressure required to convey the materials is removed from the diaphragm member 20 and the weight 31 operates lever 32 about pivot 34 and causes the diaphragm member 20, rod 21 and piston 22 to move to their original positions. This reverse movement causes piston 22 to close port to conduit 27 thereby cutting off the compressed gas or air supply. Piston 22 again in its normal position also opens conduit 28 to the atmosphere through cavity 23 of piston 22 and through air port 26. The accumulated pressure in conduit 28 is dissipated, permitting piston 41 in chamber 46 to move in direction towards forwarding chamber 10, actuated by weight 49 on lever 47, and thereby moving the valve member 42 away from valve seat 43 with the result that materials accumulated in hopper 11 are permitted to again flow freely into forwarding chamber 10. The movement of pistons 41 in cylinder 46 also permits pipe conduit 16 to be open to the atmosphere through air port 45, thus removing the pressure from pressure control chamber of valve 15. With this pressure removed the spring member 19 of the valve 15 causes it to move to its original position thereby closing off the compressed air or gas supply conduit 14. The materials again flowing into the chamber 10 cause a repetition of the cycle.

Unless the material is being removed from the delivery chamber 13 the chamber will in time become filled. To prevent congestion or overflow, a control member or means consisting of a diaphragm and valve is located in some convenient position such that the pressure of the material against the diaphragm 52 will cause it to move and by means of connecting rod 51, move valve piston 53 in cylinder 50 to a position closing port of conduit 54, thereby removing air pressure from conduit 27. Under such circumstances the cycle of operation will be stopped until material has been drawn from the delivery chamber 13 and the pressure thereby removed from the diaphragm member 52.

From the foregoing description it will be observed that the conveyer system as described and illustrated is fully automatic in operation. That is to say, so long as materials are supplied to the system they will be conveyed unless the accumulation in the delivery or storage chamber reaches the maximum capacity desired.

The use of a piston operating in a cylinder to actuate a rod member connected to a valve in a pressure chamber all for the purpose

of closing the material inlet opening by means of compressed gas or air is neither new nor novel. Such a device has been in general use for many years. I do not claim it as my invention, only in combination.

5 By connecting conduit 28 direct to pressure control chamber of valve 15, this valve closing feature may be eliminated from the conveyer system and any other desired means 10 of closing the opening beneath hopper 11, into the forwarding chamber 10, substituted.

15 The use of an auxiliary chambered valve located in the compressed gas or air supply line to control the flow of compressed gas or air dependent upon pressure variations of the conveyer system is claimed as my invention and covered by previous application as referred to in this specification, but is not claimed in this invention, only in combination.

20 Valves of the "sliding piston within a cylinder" type, also flexible members such as diaphragms which may move in response to variable pressures and return to normal position in response to weights or springs or the like, are neither new nor novel and are not claimed as my invention, only in combination.

25 I have illustrated and described herein certain apparatus which may be employed to accomplish the purpose of my invention. It is however, to be understood that various other forms of apparatus may be utilized to accomplish the purpose. Likewise that 30 many detail parts of the apparatus may be considerably modified and changed without departing from the essential features or sacrificing any of the advantages of my invention.

35 As being new and the principles exemplified by the particular example shown and which I desire to secure by Letters Patent, I claim:

40 1. In a conveyer of the class described, 45 a forwarding chamber having a discharge conduit and a compressed air supply conduit connected thereto, an inlet for filling the forwarding chamber, a valve for said inlet, that has as actuating means a piston operating in a pressure chamber, a valve having a pressure chamber control, intercepting said compressed air supply conduit, a three-way valve operatively connected to a flexible segment of wall of forwarding chamber, and a compressed air supply conduit intercepted by 50 said three-way valve and connected to the pressure chambers of the aforesaid valves.

45 2. In a conveyer of the class described, a forwarding chamber having a discharge conduit and a compressed air supply conduit connected thereto, means for admitting materials into the forwarding chamber comprising a valve actuated by a pressure chamber, a valve having an auxiliary control chamber mounted in said compressed air

55 supply conduit, a three-way valve, a member mounted in the wall of said forwarding chamber and having movement responsive to variations in gravitational weight of materials to be conveyed and operatively connected to said three-way valve, and a compressed air conduit connected to the auxiliary control chamber intercepted first by connection through said pressure chamber and second by said three-way valve.

60 3. In a conveyer of the class described, a forwarding chamber having a discharge conduit and a compressed air supply conduit connected thereto, an inlet for filling the forwarding chamber, a valve for said inlet, that has as operating means a piston operating in a pressure chamber, a valve having a pressure chamber control, intercepting said compressed air supply conduit, a conduit connection between said pressure chambers, a three-way valve operatively connected to a flexible segment of wall of forwarding chamber, and a compressed air supply conduit, intercepted by said three-way valve, and connected to pressure chamber of said inlet valve.

65 4. In a conveyer of the class described, a forwarding chamber and a delivery chamber having a conduit interconnection, a compressed air supply conduit connected to the forwarding chamber, a valve intercepting said compressed air supply conduit, that has an auxiliary pressure chamber control, a valve operatively connected to a movable member mounted in said delivery chamber, a valve operatively connected to a flexible segment of wall of said forwarding chamber, and a compressed air supply conduit connected to said pressure chamber of the first named valve and intercepted by the 70 two last named valves.

75 5. In a conveyer of the class described, a forwarding chamber having a discharge conduit and a compressed air supply conduit connected thereto, a valve having pressure chamber operating means, located in compressed air supply conduit, an inlet for filling said forwarding chamber, a valve for said inlet, having as operating means a piston acting in a pressure chamber against the reverse action of a counterweighted lever, and a valve operatively connected to a flexible segment of wall of said forwarding chamber, and intercepting a compressed air supply conduit connected to pressure chambers of the two first named valves.

80 6. In a conveyer of the class described, a forwarding chamber having a discharge conduit and a compressed air supply conduit connected thereto, a valve having a spring and pressure chamber operating means, intercepting the compressed air supply conduit, an inlet for filling said forwarding chamber, a valve control for said inlet having as operating means a piston operating in

a pressure chamber, a valve operatively connected to a flexible segment of wall of forwarding chamber, and a compressed air supply conduit, intercepted by last named valve, 5 connected to the two pressure chambers.

7. In a conveyer of the class described, a forwarding chamber and a delivery chamber having a conduit interconnection, a compressed air supply conduit connected to said

10 forwarding chamber, a valve intercepting said compressed air supply conduit, having a pressure chamber control, an inlet for filling said forwarding chamber, a valve for said inlet, that has as operating means a piston

15 ton operating in a pressure chamber, a three-way valve operatively connected to a flexible segment of wall of forwarding chamber, a valve operatively connected to a movable member mounted in said delivery chamber,

20 and a compressed air supply conduit intercepted by said three-way valve and by said last named valve and connected to the pressure chambers of the two aforesaid valves.

8. In a conveyer of the class described, a 25 forwarding chamber and a delivery chamber having a conduit interconnection, a compressed air supply conduit connected to said forwarding chamber, a valve intercepting said compressed air supply conduit, having

30 a pressure chamber control, an inlet for filling said forwarding chamber, a valve for said inlet, that has as operating means a piston operating in a pressure chamber, a conduit connection between said pressure chambers, a

35 valve operatively connected to a flexible segment of wall of forwarding chamber, a valve operatively connected to a movable member mounted in said delivery chamber, a compressed air supply conduit, intercepted by

40 the two last named valves, connected to the pressure chamber of the inlet valve.

9. In a conveyer of the class described, a forwarding chamber and a delivery chamber having a conduit interconnection, a compressed air supply conduit connected to the

45 forwarding chamber, a valve having a spring and pressure chamber operating means, intercepting the compressed air supply conduit, an inlet for filling said forwarding

50 chamber, a valve for said inlet, having as operating means a piston acting in a pressure chamber against the reverse action of a counter weighted lever, a valve operatively connected to a flexible segment of wall of

55 said forwarding chamber, a valve operatively connected to a movable member mounted in said delivery chamber, a compressed air supply conduit intercepted by the two last named valves and connected to the pressure

60 chambers of the two first named valves.

10. In a conveyer of the class described, a forwarding chamber and a delivery chamber having a conduit interconnection, a compressed air supply conduit connected to for-

warding chamber having provision for admitting materials thereto, a valve for said opening with a pressure chamber operating means, a compressed air supply conduit connected to said pressure chamber, a movable 70 segment of wall of delivery chamber, and a valve operatively connected to said segment of wall, and intercepting said last named air supply conduit.
